UNITED STATES PATENT OFFICE.

EDWARD A. JONES, OF PITTSFIELD, MASSACHUSETTS, AND ROBERT J. MARX, OF LONDON, ENGLAND.

REFINING-ENGINE.

1,272,453.

Specification of Letters Patent. Patented July 16, 1918.

Application filed June 13, 1914. Serial No. 844,900.

To all whom it may concern:

Be it known that we, EDWARD A. JONES and ROBERT J. MARX, a citizen of the United States and subject of the King of England, respectively, residing at Pittsfield, county of Berkshire, State of Massachusetts, and London, E. C., England, respectively, have invented certain new and useful Improvements in Refining - Engines, fully described and represented in the following specification and the accompanying drawings, forming a part of the same.

This invention relates to improvements in refining engines for producing paper pulp, and has been designed particularly for use with refining engines of the Jordan type, though it may be used in other types of refining machines.

The Jordan type of engine may be briefly described as comprising a stationary cone-shaped shell having an endwise adjustable cone-shaped core rotating therein and a driving mechanism for rotating the core, the shell and core being provided with coacting cutting elements which while the core rotates comminute or grind up the material which is fed into the shell at the end of minor diameter to produce pulp for the manufacture of paper.

In the manufacture of paper pulp the raw material, such as ground wood or sulfite pulp, is screened and this screened material is further refined in refining engines of the Jordan type briefly described above to finally reduce the pulp to condition for use in the manufacture of paper. By the screening operation certain coarse material, as improperly ground or digested lumps or pieces of wood, are separated out from the stock which is not in suitable condition to go to the Jordan, and this material so separated out is rejected. These "rejections" have heretofore been thrown away as waste, as they could not be properly reduced in the Jordan engines as heretofore constructed.

It is the particular object of the present invention to produce a refining engine of the type referred to which will permit of the refining of such "rejections" or screenings of such as ground wood or sulfite pulp, and convert them into pulp suitable to go to the paper machines for the manufacture of paper.

It is also an object of the invention to provide an improved engine of the type re-

ferred to which may be employed with regular stock to produce a superior product and more efficiently than engines heretofore constructed.

With these and other objects in view, the invention generally consists in the employment in a Jordan engine of a plug having grinding bars composed of basalt lava or similar stone, and a shell having coöperating grinding bars composed of similar material, these bars being arranged in the plug and in the shell in a novel manner so as to provide an improved grinding or disintegrating effect.

Constructions embodying the invention also include novel methods of securing the grinding bars in the shell and plug.

For a complete understanding of the invention, reference may be had to the accompanying drawings which show the preferred embodiment of the invention as used with a refining engine of the Jordan type, and a detailed description of these drawings will now be given.

Referring to said drawings—

Figure 1 is a sectional elevation of a refining engine embodying the improvements;

Fig. 2 is a cross section of the same on the line 2—2, Fig. 1, the section being taken through the core and shell and showing the arrangement of the stone grinding bars;

Fig. 3 is an elevation of the plug or core;

Fig. 4 is a sectional plan view showing the interior of the shell to illustrate the novel arrangement of the stone grinding bars therein;

Fig. 5 is an end view of the plug or core, and

Fig. 6 is a cross section of the shell at the smaller, or intake, end, the section being taken on line 6—6 of Fig. 4.

Referring now to the drawings, the invention has been shown as employed with an engine of the Jordan type, the parts of which are supported on a base 1 of any suitable or desired construction. The refining engine shown comprises a stationary cone-shaped shell 2 supported in any suitable manner, as by standards 3, rising from the machine bed 1, and a cone-shaped plug or core which is supported to rotate within the shell 2. This core 4 is mounted on a shaft 5 journaled in suitable bearings 6 supported in standards 7 on the base 1. This shaft is mounted to have an endwise adjusting

movement relatively to the plug, as is common in this type of machine, this endwise adjustment being given it by any suitable or usual mechanism, a description of which 5 will be unnecessary for an understanding of the present invention, and therefore not shown. The ends of the shell are closed in any suitable manner, as by heads 8, 9, the latter of which is located at the outer or 10 delivery end of the machine, and is provided with a delivery outlet 10. The other head 8 at the inlet end of the machine is formed to provide a feed chamber 11 which is supplied through a throat 12 from a hopper 13. 15 When machines of this type are to be employed for refining "rejections" or screenings of ground wood pulp or sulfite pulp screenings and the like, which are relatively coarse, preferably a feeding device, as a 20 screw propeller 14, is provided, which is carried on the shaft 5 before referred to, this screw acting to feed these coarse "rejections" or screenings to the shell. Likewise, when the machine is used for refining material of this character, the feed throat 12 is of 25 large dimensions to provide a free feed of the stock. This feeding device may also be employed in refining stock other than "rejections" or screenings from ground wood or 30 sulfite pulp, if desired, but its use may, if desired, be omitted. Suitable means for rotating the shaft 5, and, with it, the core 4, may be employed, the shaft being rotated in the construction shown by a pulley 15 driven 35 from a suitable source of power.

In machines of the type described, the shell and plug are provided with coöperating grinding or disintegrating elements. In accordance with the invention, the shell and 40 plug are provided with coöperating grinding bars which are composed of basalt lava or similar stone, this material having been found to have certain advantages over bars of metal for refining coarse material as the 45 "rejections" from ground wood or sulfite pulp. These stone bars are arranged in the shell and core in a novel manner, it having been found in practice that the bars arranged as about to be described, effectually 50 reduce the screenings or "rejections" of ground wood or sulfite pulp to a stock suitable to be run to the paper machines. The form and number of the grinding bars may vary in the plug and shell, and they may be 55 of various configurations and mounted in the shell and plug in different ways respectively to secure the desired results.

In the construction illustrated, and referring first to the plug shown best in Figs. 2, 60 3, and 5, the plug consists of a hollow shell of iron or other suitable material 16 which is formed with a plurality of longitudinal grooves 17 having between them projections 18 provided with inwardly sloping sides 19 65 forming overhanging shoulders or abut-

ments 20. These grooves are provided around the periphery of the roll in sufficient number to accommodate the required number of the stone grinding bars. These grinding bars are marked 21 and are inserted in 70 the grooves 17, and each grinding bar is for convenience made in two sections *a*, *b*. In the preferred construction, these grinding bars increase in width from the inlet or small end of the plug to the outlet or large end, 75 as shown in Fig. 3, and preferably are likewise similarly increased slightly in thickness, this construction in practice having been found to produce the best results.

The grinding bars are secured in the recesses in any suitable manner. In the construction illustrated (see Fig. 2) the grinding bars are provided on each side with a notch or groove 22, and they are anchored in the grooves 17 by a filling of cement or 80 other suitable plastic holding material 23. The cement fills in around the abutment shoulders 20 of the projections 18 referred to and into the grooves or notches 22 in the bars. A small amount of cement is likewise 85 filled in to cover the top surface of the projections 18, as shown in Fig. 2. With this construction, the bars are effectually anchored against displacement in the grooves or slots, the cement covering the top of the 90 projections not being filled in flush with the edges of the bars (see Fig. 2), but to some extent below them, so as to leave grinding edges and recesses between such grinding edges, these recesses acting to assist in cir- 100 culating the stock through the machine.

The shell is, as before stated, likewise provided with a plurality of grinding bars of basalt lava or other similar stone, which, like the bars of the plug, are arranged in 105 the shell in a novel manner.

The exact arrangement and means of securing the bars in the shell may be somewhat varied. To produce an efficient grinding effect, the bars are arranged in the machine 110 in what may be termed sets, that is, there are provided a plurality of bars arranged end to end extending longitudinally the length of the shell. For convenience in construction, preferably these sets are arranged 115 in groups, an arrangement being adopted whereby the bars of one group, which may be alike and similarly arranged, are in staggered relation longitudinally of the shell with the bars of the succeeding groups. 120 Four such groups are shown (Fig. 2) indicated by the numerals 24, 25, 26, and 27, each group comprising a number of rows or sets of bars. The bars of each of these groups are alike and similarly arranged, 125 and the bars of one group are in staggered relation longitudinally of the shell with the bars making up the succeeding group. While such arrangement is efficient and convenient, other arrangements may be adopted, 130

as, for instance, as by staggering each set of bars with relation to the succeeding set.

In the particular construction illustrated, (see Figs. 2 and 4) the bars of group 24, 5 each of which for convenience has been numbered 24, are three in number arranged end to end longitudinally of the shell, and of a suitable number around or peripherally of the shell. The bars nearest the small or 10 inlet end of the shell are preferably staggered with relation to the next bars longitudinally, and the bars preferably increase in width from the inlet or small end of the shell toward the outlet end. The bars of 15 the next succeeding group, as 25, are, as shown in Fig. 4, arranged in fours longitudinally of the shell, these bars being shorter than the bars of the group 24 and thus being in staggered relation longitudinally of the 20 shell with the bars 24. These bars 25 likewise may be arranged in staggered relation to each other longitudinally of the shell, and as some of them are shown, and these bars likewise increase in width from the 25 inlet end to the outlet end of the machine. The next succeeding group or section 26 may have its bars arranged like the bars of group 24, and the last group 27 may have its bars arranged like the group 25. With 30 this construction, and by staggering one group of bars with relation to the next succeeding one longitudinally of the shell, a very efficient grinding surface is produced.

The grinding bars may be secured in the 35 shell in any suitable manner, as by beveling the sides of the bars as indicated at 28 and locking them in position with short wedges 29 of wood or other suitable material driven in on each side of the bars. In the preferred construction, and as shown, when the 40 bars are arranged in groups, bars of iron or other suitable material 30 will be provided which divide the shell into sections and are secured to the shell by screws 31, or in any 45 other suitable manner. Coöperating with these iron bars are master wedges 32 extending the length of the shell and provided with grooves 33 driven over the bars 30, this construction, with the independent 50 wedges 29, effectually locking the bars firmly in place and preventing them from becoming loosened, or working around the interior of the shell.

It has been found in practice that the 55 capacity of a refining engine of given size can be materially increased by an increase in the number of feeding notches or grooves between the bars. This result can be obtained by increasing the number of bars around the 60 plug, thus increasing the notches between the bars. When these bars are made of basalt lava stone, however, they have to be of a substantial width to stand the working strain, and it is therefore impracticable to 65 materially increase the number of these bars

in a refining engine without unduly increasing the size of the plug and shell. When, therefore, machines constructed in accordance with the invention are provided with grinding bars of basalt lava stone, means 70 will be provided for facilitating the feed and thereby increasing the capacity of the engine, without increasing the number of bars. This is accomplished by providing the bars of the plug with feeding notches 75 or grooves. The bars may be arranged, as shown, as two in number lengthwise of the plug, one of the bars being in the particular construction illustrated shorter than the other. In the best constructions, the short 80 bar *a* will be provided with one groove marked *c*, and the longer bar *b* will be provided with two of such grooves, these grooves running parallel with the length of the bars. In the best constructions, the 85 grooves in the bar *b* will be in staggered relation with the groove in the bar *a* so as to prevent the stock from running through the grooves without being subjected to the 90 grinding action.

In the best constructions, where the grinding elements of the shell are basalt lava bars, these bars may, like the bars in the plug, be provided with longitudinally-extending feeding notches or grooves. Such 95 grooves are shown in the drawing marked *d*.

With the construction shown and described, a very efficient grinding machine is produced, and one by the employment of which material heretofore wasted can be 100 made suitable for paper pulp ready to go to the paper machine. While the invention has been described in its preferred form, it will be understood that various changes in the particular arrangement of the bars in 105 both the plug and shell may be made without departing from the invention, and that such changes and variations may be made as desired.

What is claimed is:

1. In a refining engine, a shell provided with groups of grinding bars arranged circumferentially of the shell, each group being made up of sets of bars arranged longitudinally of the shell with their ends abutting, the number of sets in one group being different from those of a succeeding group, and the sets in one group being in staggered relation with respect to the sets in a circumferentially adjacent group. 110

2. In a refining engine, a shell provided with groups of grinding bars arranged circumferentially of the shell, each group being made up of sets of bars arranged longitudinally of the shell with their ends abutting, the number of sets in one group being different from those of a succeeding group, the sets in one group being in staggered relation with respect to the sets in a circumferentially adjacent group, and the bars of 115 120 125 130

certain of the sets of each group being in staggered relation at their ends with the bars of an adjacent set in the same group.

3. In a refining engine, a shell provided with a plurality of groups of bars arranged around the shell, each group made up of sets of bars arranged longitudinally of the shell, the bars of each group being in staggered relation with the bars of the succeeding group longitudinally of the shell, wedge keys between the groups for anchoring them extending the length of the shell, and shorter wedges for anchoring each of the bars.

4. In a refining engine, a shell provided with groups of grinding bars arranged circumferentially of the shell, each group being made up of sets of bars arranged longitudinally of the shell with their ends abutting, the number of sets in one group being different from those of a succeeding group, the sets in one group being in staggered relation with respect to the sets in a circumferentially adjacent group, and a coöperating core.

5. In a refining engine, a core or plug comprising a shell having a grooved periphery, grinding bars in the grooves, said grinding bars being provided with longitudinally extending holding grooves in the sides, and cement filled into the grooves in the shell and grooves in the bars for locking the bars in the grooves.

6. In a refining engine, a core or plug provided with a plurality of grooves, sets of stone grinding bars in the grooves, each set comprising two bars increasing in width from one end to the other of the core, and means independent of the bars for anchoring the bars in the grooves.

7. In a refining engine, a core or plug having a plurality of grooves, sets of stone grinding bars in the grooves, one set for each groove, each set consisting of a plurality of bars increasing in width from one end to the other of the grooves, notches in the sides of the bars, and cement filling the grooves and the notches in the bars for anchoring the bars in the grooves.

8. In a refining engine, the combination of a shell, a plurality of sets of stone grinding bars in the shell, each set including a plurality of bars arranged longitudinally thereof, the bars of one set being in stag-

gered relation longitudinally with the bars of a succeeding set, a core or plug mounted to rotate in the shell and having a plurality of sets of stone bars coöperating with the bars of the shell, and a propeller for feeding material to the shell.

9. In a refining engine, the combination with a shell, of a plurality of sets of stone grinding bars arranged longitudinally of the shell, said bars increasing in width from the inlet end of the shell to the outlet end, grooves in the bars, the grooves in certain of the bars breaking joint with the grooves of other of the bars, and a core or plug mounted to rotate in the shell and having a plurality of stone grinding bars increasing in width from the inlet end of the shell to the outlet end.

10. In a refining engine, the combination with a shell, of a plurality of sets of stone grinding bars arranged longitudinally of the shell, said bars increasing in width from the inlet end of the shell to the outlet end, grooves in the bars, the grooves in certain of the bars breaking joint with the grooves of other of the bars, and a core or plug mounted to rotate in the shell and having a plurality of bars extending longitudinally thereof, grooves in the bars breaking joint with each other, the bars increasing in width from the inlet end to the outlet end.

11. In a refining engine, a core or plug having a plurality of grooves, sets of stone grinding bars in the grooves, one set for each groove, each bar being provided with a feeding notch extending longitudinally thereof.

12. In a refining engine, a core or plug having a plurality of bars extending longitudinally thereof, one bar being provided with a longitudinally-extending feeding notch and the next succeeding bar being provided with a plurality of longitudinally-extending feeding notches breaking joint with the feeding notch in the preceding bar.

In testimony whereof, we have hereunto set our hands in the presence of two subscribing witnesses.

EDWARD A. JONES.
ROBERT J. MARX.
